US0D1050717S

(12) United States Design Patent (10) Patent No.: US D1,050,717 S
(45) Date of Patent:  Nov. 12, 2024

(54) BACKPACK

(71) Applicant: PSICHOGIOS PUBLICATIONS S.A.,
Metamorfosi (GR)

(72) Inventor: Haralampos Psichogios, Attica (GR)

() Term: 15 Years

(21) Appl. No.: 35/520,085

(22) Filed: Feb. 2, 2024

(80) Hague Agreement Data

Int. Filing Date: Feb. 2, 2024

Int. Reg. No.: DM/235168

Int. Reg. Date: Feb. 2, 2024

Int. Reg. Pub. Date: Feb. 23, 2024

(51) LOC (14) Cl. 03-01

(52) U.S. Cl.

USPC D3/216

(58) Field of Classification Search

USPC D3/201, 215, 216, 217

CPC .. A45F 3/04; A45F 3/042; A45F 3/047; A45F 2003/001

See application file for complete search history.

Primary Examiner — Steven J Czyz

(57) CLAIM

The ornamental design for a backpack, as shown and described.

DESCRIPTION

The patent or application file contains at least one drawing executed in color. Copies of this patent or patent application publication with color drawing(s) will be provided by the Office upon request and payment of the necessary fee.

1. Backpack

1.1: Right side view of a backpack

1.2: Right side view of the backpack, shown with a hood deployed

1.3: Top view of the backpack

1.4: Bottom view of the backpack

1.5: Front view of the backpack

1.6: Perspective view of the backpack

1.7: Rear view of the backpack

1.8: Front view of the backpack, shown with a cape deployed

1.9: Front view of the backpack, shown with a hood deployed

1.10: Front view of the backpack, shown with a hood deployed and in an alternate state

1.11: Left side view of the backpack

1.12: Left side view of the backpack, shown with a hood deployed

A backpack, incorporating also a hood and a cape that are completely stored away in hidden pockets within the bag; the hood and cape are water resistant and, when unfolded, may be used on the one hand as an anorak for the person carrying the bag, and on the other hand as a role-play game.

1 Claim, 12 Drawing Sheets
